UNITED STATES PATENT OFFICE

FRANCIS J. McCANN, OF EDMONTON, ALBERTA, CANADA, ASSIGNOR TO HEART-STOOKER COMPANY LIMITED

SHOCK-FORMING MACHINE

Application filed January 4, 1929. Serial No. 330,293.

This invention relates to a machine for shocking grain in the field as it is delivered from a harvester and binder to which the machine is attached and more particularly to means for depositing and evenly distributing sheaves of grain in a receptacle in the machine.

Heretofore in machines of the type herein disclosed the sheaves of grain have been conveyed from the binder to the shock former by means of elevators in the form of an endless conveying chain or belt. However the method has been found objectionable in that the sheaves tend to bunch and pile up in the receptacle directly below the point of discharge from the conveyor.

It is therefore an object of the invention to provide a device for distributing the sheaves in a receptacle in the machine without employing the usual elevator, this result being attained by the use of a cradle and a novel mechanism for operating the same.

A further object of the invention is to provide means for evenly distributing the sheaves in a bin or receptacle so that the capacity of the bin or receptacle may be efficiently utilized.

A further object of the invention is the provision of a construction and arrangement of parts which enables the sheaves or bundles to be deposited in shock formation with the least amount of tractive effort thus reducing the tendency to retard the forward movement of the machine.

These and other objects are attained by the novel construction, combination and arrangement of parts hereinafter described and shown in the accompanying drawing constituting a material part of this disclosure in which:

Figure 1 is a side elevation of the machine in its normal position;

Fig. 2 is an elevational view of the opposite side of the machine;

Fig. 3 is a plan view of the machine;

Fig. 4 is a front end view of the machine;

Fig. 5 is a perspective view of mechanism designed to cause the sheaves to be evenly distributed as they are deposited in a bin or receptacle;

Fig. 6 is a plan view of a clutch and gear device used in the machine and

Fig. 7 is a side view of the clutch and gear device.

At the forward end of the machine and carried by the main frame 1 is a trough having a vertical side wall 2, and an inclined wall 3 the trough being adapted to receive bundles or sheaves as they are ejected from the binder (not shown). The wall 2 acts as a back plate for the bundles while the lower inclined wall 3 enables the easy entrance of the bundles from the binder.

Attached to the frame 1 are vertical struts 4, 5, which support a horizontal member 6, the latter having its rear end inclined upwardly at 7 as shown in Fig. 1 to serve as a support for mechanism used in the operation of a tilting receptacle. The structure of the receptacle and the mechanism referred to form no part of this invention.

A cross bar 8 connects the frame member 1 to a frame member 9 inclined thereto, the frame structure being further strengthened by the members 10, 11. Attached to members 10 and 11 are upstanding bearing supports 12, 13 upon which is pivotally mounted a bin or receptacle 15, the latter being normally open at the top to allow the introduction of bundles or sheaves.

Fixed to supports 4, 4' respectively are bearings 16 and 17, in which is journaled a shaft 18 (see Fig. 5). Attached intermediate of shaft 18 is a casting 19, in which is journaled a vertical shaft 20, the lower end of which shaft is attached to an arcuate brace 21 of a cradle.

The cradle comprises a plurality of arcuate braces similar to brace 21, upon which are positioned a plurality of wooden slats 22, the forward end of the cradle being provided with an end plate 23, (see Fig. 4).

The cradle is normally positioned in the trough between the walls 2 and 3 so that it may receive bundles from the binder.

Referring again to Figures 3 and 5, the shaft 20 has fixed thereto, intermediate of its length, a pair of brace bars 24, 25 which are also fixed to sides of the cradle.

Attached to a collar 26 connected with the

arcuate brace 21 and shaft 20 is a link 27, which is fixed to arm 28 of a rockshaft 29, the latter passing through an aperture 30 in wall 2 and being journalled in bearings 31, 32 supported by frame members 1 and 10.

- 5 Fixed to shaft 29 is a gear 33 which meshes with a segmental gear 34, the latter being non-rotatably mounted on a stub shaft 35 journalled in a bearing 36 mounted on support 4.
- 10 A crank arm 37 is fixed to shaft 35 and pivotally connected to a link 38, which in turn is pivotally connected to a crank arm 39, fixed to shaft 40, the latter being journalled in bearing 41 on frame member 1. The shaft 15 40 is keyed to the male member 42 of a clutch upon which is pivotally mounted a rocker member 45, comprising an arm 46 and an engaging roll 47, (see Figures 6, 7) which is normally urged into engagement with the 20 female clutch member 43 by a compression spring 44 bearing against the rocker member 45 and a hub integral with the male member 42.

The rocker arm 46 projects beyond the periphery of male member 42 and is adapted to engage an arm 48, which is connected to a rock shaft 49 journalled on frame member 50, the rock shaft 49 also having a crank arm 51 by which it may be operated.

25 30 It will be seen that when the arms 46 and 48 are in engagement, the clutch will be disengaged, and when the shaft 49 is rotated by means of crank arm 51, to break the engagement between the arms, the spring 44 will 35 cause the engagement of the male and female clutch members.

The periphery of the female member 43 is provided with sprocket teeth 52 in engagement with a chain 53, the latter passing over 40 a sprocket 54 connected to the drive wheel 55 of the machine.

In operation, when it is desired to discharge bundles from the cradle into the receptacle 15, the male member 42 is allowed to engage 45 the female member 43 of the clutch, which action will cause the drive wheel, through the intermediate mechanism, to rotate arm 39, to pull link 38 forward and rotate segmental gear 34 and gear 33, to rock the shaft 29 and 50 lift the cradle to a position as shown in Figure 1 in dotted lines, to discharge the bundles into the receptacle.

The shaft 40 will be rotated one revolution after which the arms 46 and 48 are again 55 engaged to release the clutch. A spring 56 has one end connected to the frame of the machine and the other end connected to the pivot for link 38 and crank arm 39 to hold the weight of the link and crank arm to prevent them from falling back and causing the clutch to jerk.

When crank arm 39 is rotated through one revolution, the arm 37 and segmental gear 34 are moved through one third of a revolution 60 and back again to their original positions.

The gear 33 is moved through two-thirds of a revolution, and the crank 28 raises the cradle through one-half revolution to the position shown in dotted lines in Figure 1, to deposit the sheaves in the receptacle, and then returns to its initial position. Spikes 57 are carried 70 in the bottom of the cradle to keep the sheaves in position while the cradle is being raised. (Fig. 4).

In order to evenly distribute the sheaves in 75 the receptacle the cradle is swung successively into three positions, to the right, to the center and then to the left. To accomplish this result the following mechanism is employed.

80 Referring to Figure 5, it will be noted the upper end of connecting rod 20 has fixed thereto a crank arm 58, pivotally connected to a link 59, which in turn is pivotally connected to a crank arm 60, fixed to one leg of 85 a U-shaped member 61, the leg being rotatably mounted in a bearing 62 mounted on the support 63. The other leg of the member 61 is pivotally connected to a link 64, the latter being pivotally connected to a lever 65 pivoted to a cross bar 66 attached to wall 2 and the support 4. Carried by lever 65 is a pair of rollers 67 which engage a cam 68 on a drum 69. The drum 69 is provided at one end with three equally spaced notches 70 adapted 90 to be engaged by a pawl 71 pivoted to a crank arm 72 fixed to shaft 18. The other end of the drum is provided with three equally spaced notches 73 adapted to be engaged by holding pawl 74 pivotally mounted on the 95 adjacent support 63.

100 From the above description it will be seen that when shaft 18 is rotated clockwise (Fig. 5) during the return of the cradle to its initial position, the pawl 71 will engage one of the notches 70 to rotate the drum one-third of a revolution, the drum being rotatably mounted on shaft 18. This movement of the drum causes cam 68, through rollers 67, to move lever 65 from extreme right to centre position. During the next one-third revolution of the drum the lever will be moved from centre to extreme left, and so on. The movements of the lever cause similar movements of the U-member 61 to rotate connecting rod 105 110 115 20 in the casting 19, and shift the cradle from left, to center, to right, etc. so that with each depositing operation of the cradle, the sheaves will be deposited in either the left, centre or right section of the receptacle 15.

120 When the receptacle has been filled, the sheaves will be discharged therefrom in an upright position on the ground by a mechanism herein shown, but not described, such mechanism forming no part of this invention.

125 The foregoing disclosure is to be regarded as descriptive and illustrative only, and not as restrictive or limitative of the invention, of which, obviously, an embodiment may be constructed including many modifications with- 130

out departing from the scope herein indicated and denoted in the appended claims.

Having thus described my invention, what I claim as new and desire to secure by Letters Patent is:

5. 1. In a shocking machine, a receptacle, a cradle upon which sheaves may be deposited, a connecting rod attached to the cradle, a link fixed to the connecting rod, a rock shaft to which the link is pivotally connected, a pinion fixed to the rockshaft, a segmental gear meshing with said pinion, an arm connected with said gear to rotate therewith, a crank, a link connecting the crank and arm, 10 a shaft to which the crank is fixed, a male clutch member keyed for sliding movement on the shaft, a female clutch member, resilient means urging the clutch members into engagement, means to normally prevent engagement of said clutch members, and chain and sprocket connections between the female member and a drive wheel of the machine.

20 2. In a shocking machine, a receptacle, a cradle upon which sheaves may be deposited, a connecting rod attached to one end of the cradle, a rockshaft connected with the connecting rod, a pinion fixed to the rockshaft, a segmental gear meshing with said pinion, a male clutch member, means connecting the gear and the male clutch member, a female clutch member, means for resiliently urging the clutch members into engagement and means for driving the clutch from a drive wheel of the machine.

35 3. In a shocking machine, a receptacle, a cradle upon which sheaves may be deposited, and means driven by the drive wheel of the machine to rotate the cradle.

40 4. In a shocking machine, a receptacle, a cradle upon which sheaves may be deposited, a shaft, a casting fixed to the shaft, a connecting rod journalled in the casting and attached to one end of the cradle, means connected with the drive wheel of the machine to rotate the cradle and the shaft, a cam carried by the shaft, a lever positioned adjacent the cam, means for oscillating the lever by the cam, and means connecting the lever and the connecting rod so that the oscillating movements of the lever will be transmitted to the cradle.

45 5. In a shocking machine, a receptacle, a cradle upon which sheaves may be deposited, a shaft, a casting fixed to the shaft, a connecting rod journalled in the casting and attached to one end of the cradle, means connected with the drive wheel of the machine to rotate the cradle and the shaft, a cam rotatably mounted on the shaft, means fixed 50 to the shaft to rotate the cam, a lever pivoted adjacent the cam, means to oscillate the lever by the cam, a U-shaped member to one leg of which the lever is connected, a crank arm connected to the other leg of the U-shaped member, and means connecting the crank arm

and the connecting rod so that oscillating movements of the lever will be transmitted to the cradle through the connecting rod.

6. In a shocking machine, a receptacle, a cradle upon which sheaves may be deposited, a connecting rod attached to one end of the cradle, a rockshaft connected with the connecting rod, a pinion fixed to the rockshaft, a segmental gear meshing with said pinion, a male clutch member, means connecting the gear and the male clutch member, a female clutch member, means for resiliently urging the clutch members into engagement, an arm projecting from the male member, a lug pivotally mounted adjacent the clutch to engage said arm to cam the clutch members from engagement, and chain and sprocket means for connecting the female member with a drive wheel of the machine.

Signed at Edmonton, Alberta, Canada, this 27th day of December, 1928.

FRANCIS J. McCANN.
